KEY HOLDER

John M. Bennett, Detroit, Mich.

Application February 16, 1935, Serial No. 6,833

6 Claims. (Cl. 59—96)

My invention relates to a new and useful improvement in a key holder and forms in part a continuation of my application Serial No. 698,966 filed November 21, 1933 and in part a continuation of my application 704,864 filed January 2, 1934 and particularly in so far as the key holder is adapted for retaining keys in position for ejection from opposite edges of the holder.

In addition to providing a key holder in which such function may be attained, it is also an object to provide in a key holder of this class, key-ejecting springs which will serve the function of ejecting the keys outwardly of the holder and at the same time, through frictional engagement, will serve to retain the latch members accurately located so that the swinging of a key inwardly of the holder will always engage the latch member at the proper position.

It is another object of the present invention to so form the supporting body on which the latch springs are mounted, that a minimum area of the latch springs will be in contact with the supporting body, so that a maximum length for flexing will be provided.

Another object of the present invention is the provision of yieldable attaching means which will serve as a pivot and which are, through their own body, mounted and located in position.

Other objects will appear hereinafter.

The invention consists in the combination and arrangement of parts hereinafter described and claimed.

The invention will be best understood by a reference to the accompanying drawing which forms a part of this specification and in which,

Fig. 1 is a plan view of the invention with one of the side walls removed.

Fig. 2 is a sectional view taken on line 2—2 of Fig. 1.

Fig. 3 is a fragmentary sectional view taken on line 3—3 of Fig. 1.

Fig. 4 is a perspective view of one of the key retaining members.

In the device I provide a supporting body 7 mounted on opposite faces of which are the covers 8 and 9. Mounted on a reduced portion 10 of the supporting body, is a U-shaped spring providing the legs 11 and 12 which carry latch noses 13 and 14 respectively. It is these latch noses which serve to engage the key when it is swung into position between supporting body 7 and the cover 8 or 9. A spring 15 is inserted in the slit 16 formed in the supporting body and this spring, being U-shaped, is provided with the bowed legs 17 and 18 which serve to engage the key and eject

the same from between the cover and the supporting body when the key is released from the latch. When the key is swung downwardly between the cover and the supporting body, the leg 17 or 18 is flexed inwardly and placed under tension. Each of the latch legs 11 and 12 is provided with a tubular member 19 on which is mounted the press button 20 which extends through the opening 21, formed in the cover. By pressing the press button 20 inwardly, the legs 10 11 and 12 are brought into approach so that the latch nose will clear the key portion engaged and permit the spring 17 or 18 to eject the key outwardly. It will be noted from Fig. 1 that the springs 17 and 18 rest in engagement with the 15 legs 11 and 12 when they are spread outwardly into their normal position, and these members 17 and 18 resist further spreading of these legs. The purpose of this is to prevent an undue spreading of the legs so that this latch nose would not 20 be in the proper position when the key is swung inwardly into position between the supporting body and the cover. The key when swung inwardly should strike the inclined portion of the latch nose. If these legs, however, were permitted to spread apart further than their normal position, the key would strike the latch on the end rather than on the inside portion, with the result that a very unsatisfactory operation of the device would be present. This engagement of the 25 springs 17 and 18 with the legs 11 and 12, forms a part of this invention and they serve as guides to resist undue spreading of the legs.

It will be noted that the portion 10 about which the latch legs are positioned, is cut away 35 to provide the beveled surfaces 22 and 23. In my prior structure this portion 10 had its opposite faces extend parallel, with the result that the legs 11 and 12 were in contact with the member 10 throughout a considerable area, and the flexing 40 of the legs 11 and 12 took place from the inner edge of the portion 10, whereas in the present structure, the flexing takes place at a point adjacent the outer edge of the portion 10. This, experience has shown, will result in greater life 45 in the members 11 and 12 and a more satisfactory service in all of their functions.

In Fig. 4 I have illustrated the resilient retaining member which serves to retain the keys in position. This consists of a strip of resilient material doubled upon itself to provide the legs 24 and 25, which are positioned in embracing relation on the portion 26, so that the larger portion of the legs overlies the slot cut in the supporting body. In my prior structure, I had these legs 55

24 and 25 bent inwardly toward each other at right angles to lie in engagement with one face of the portion 26. In the present structure, this inward bending has been eliminated, and I have punched inwardly from each of the legs, a lug 27 which lies in engagement with the edge of the portion 26 and serves to lock the key retainer in position. This affords a more satisfactory operation than the device with the legs bent inwardly, as well as one which is more economical to manufacture. By punching the tongues out of the metal instead of bending, a crystallizing of the metal is avoided, and the resiliency of these members 24 and 25 is retained in its normal condition. Furthermore, in assembly, the operation becomes simpler with the tongues than with the angularly turned portions.

The knobs 28 formed on the legs 25 and 24 serve to enter into the eyelet of the key and retain the same in position. With this type of mounting, the key may be slipped inwardly in the space 29 between the supporting body 7 and the cover 8 or 9. This will serve to retain the key in position on the key holder, and form a pivot for the key, while at the same time, permitting easy removal and replacement of the key. It will also be noted that the leg 24 is longer than the leg 25. This permits these parts, when pressed inwardly at their free ends, to overlap, thus affording a greater clearance for a key when inserted or removed therefrom.

It will be noted that there are two sets of members 15 with the spring legs formed thereon, and that there are two sets of the latch legs 11 and 12. A pair of latches are positioned at opposite edges of the retainer so that a pair of keys may be mounted on the retainer A and also on the retainer B to swing inwardly of the upper edge. This permits the formation of a key holder adapted to accommodate four keys while the key holder itself is maintained of minimum width. This is due to the fact that the opposite edges of the key holder serve as ejecting spaces for a pair of keys.

While I have illustrated and described the preferred form of construction, I do not wish to limit myself to the precise details of the structure shown, but desire to avail myself of such variations and modifications as come within the scope of the appended claims.

Having thus described my invention what I claim as new and desire to secure by Letters Patent is:

1. A key holder of the class described, comprising: a supporting body; a cover mounted on said body on opposite sides thereof in spaced relation thereto; a U-shaped resilient member posi-

tioned in embracing relation over one side of said body and extended to the opposite side thereof; an outwardly projecting latch nose on each leg of said U-shaped member at the end thereof, said legs being flexible inwardly toward each other against the resiliency of the material from which made; and means positioned between said body and the covers for engaging said legs and limiting the springing apart of said legs. 5

2. A key holder of the class described, comprising: a supporting body; a cover mounted on opposite faces of said body in spaced relation thereto; a pair of resilient members mounted on said body and each extended between said body and one of said covers; a latch nose on the free end of each of said members; an ejecting spring positioned between the cover and each of said members and normally engaging therewith for limiting outward flexing of said members. 10

3. A key holder of the class described, comprising: a supporting body; a pair of covers mounted at opposite faces of said body in spaced relation thereto for overlying said body; a spring positioned in the space between each of said covers and said body; a pair of resilient latch nose bearing members mounted at one of their ends on said body and extended into the space between the body and said covers and normally engaging one of said springs, said springs resisting flexing of said members beyond a predetermined distance 20 in one direction. 25

4. A key holder of the class described, comprising: a supporting body; a pair of covers mounted at opposite faces of said body in spaced relation thereto; a pair of resilient latch nose bearing members mounted on said body and each extended into the space between said body and said covers; and means carried by said body and engageable with said members for resisting flexing of the same beyond a predetermined distance 30 in one direction. 35

5. In a key holder of the class described, a supporting body; a U-shaped resilient member mounted on said body in embracing relation, said body at the point of mounting of said member 40 having its faces extended non-parallel to each other, said faces converging in the direction of the legs of said member. 45

6. In a key holder of the class described, a supporting body having a slot cut therein; a key retainer comprising a U-shaped resilient member mounted on said body in straddling relation and having its legs extended for overlying said slot; and a lug punched from each of said legs and engaging said body at the end of said slot for 50 preventing longitudinal movement of said legs in one direction. 55
